UNITED STATES PATENT OFFICE.

HARRY D. EDWARDS, OF LARCHMONT, NEW YORK, ASSIGNOR TO THE HILL COMPRESSOR & PUMP COMPANY, OF NEW YORK, N. Y., A CORPORATION OF DELAWARE.

ROTARY PUMP.

Application filed April 30, 1923. Serial No. 635,523.

To all whom it may concern:

Be it known that I, HARRY D. EDWARDS, a citizen of the United States, residing at Larchmont, in the county of Westchester 5 and State of New York, have invented a new and useful Improvement in Rotary Pumps, of which the following is a specification.

This invention relates to those rotary 10 pumps which have a gear with external teeth that is surrounded by a gear with internal teeth, one gear having more teeth than the other and the two gears being mounted eccentrically with relation to each other and 15 so intermeshing that when driven, fluid admitted through the enclosing casing on the intake side will be compressed and delivered through the casing on the discharge side.

20 In this type of pumps it is essential, in order that the gear teeth be properly engaged for effective pumping, that the amount of eccentricity of the gears be such that the pitch circles of the gear teeth be 25 tangent with each other at one point.

The object of this invention is to provide a pump of this character with means whereby the eccentricity of the gears with relation to each other may be accurately fixed, and 30 thus the proper co-operation of the gear teeth ensured to effect efficient pumping action.

This object is attained in the embodiment 35 of the invention illustrated by mounting the externally toothed gear which is surrounded by the internally toothed gear, on an arbor that is supported eccentrically of the axis of the internally toothed gear, and providing means whereby the eccentricity of said arbor 40 may be varied to enable the exact required position of the externally toothed gear with relation to the internally toothed gear to be obtained and retained.

In the accompanying drawings Fig. 1 45 shows a longitudinal section of one form of pump constructed according to this invention. Fig. 2 shows, on a larger scale, a face view of the gears that may be used, and 50 illustrates diagrammatically the shapes of the engaging gear teeth and eccentricity of

the gears. Fig. 3 shows diagrammatically in full lines the pitch circles of the gear teeth when so adjusted that the eccentricity of the gears is correct, and illustrates in dotted lines a possible position of the pitch circle of the externally toothed gear before it is properly adjusted to the pitch circle of the internally toothed gear.

In the form of the invention illustrated the pump casing 1 is cylindrical and it has a head 2 fastened in such manner that it may be removed to allow access to the interior of the gear chamber in the casing. Through the head to the gear chamber is an intake opening 3 and a discharge opening 4. In the gear chamber is a gear 5 with external teeth 6, and a gear 7 with internal teeth 8 that surround and mesh with the external teeth. For the purpose of manufacture the internal teeth are cut in a ring 70 that is forced into the gear body 7. The internally toothed gear has a central hub 9 that is supported by bearings 10 in the casing, and that is keyed to the driving shaft 11. The externally toothed gear is shown as 75 arranged to turn on bearings 12 mounted on an arbor 13 which has a journal 14 that is after adjustment locked in the head.

The internally toothed gear and the driving shaft are axially concentric, and the externally toothed gear and its arbor are axially concentric, but the axis of the arbor is eccentric to the axis of the driving shaft so that the axes of the gears will be eccentric, and the axis of the journal is eccentric with the axis of the arbor and also eccentric with the axis of the shaft so that the eccentricity of the arbor and shaft, or of the two gears, may be adjusted to an exact degree by rotating the journal.

In the particular example illustrated the externally toothed gear has eight teeth and the internally toothed gear has nine teeth. This number of teeth is not essential to the invention, nor is the exact shape of the teeth.

The addendum sections 15, or the portions beyond the pitch circle 16 of the teeth of the inner gear shown, are formed on epicycloidal curves, that is, curves traced by a

point on the circumference of the circle 17 which rolls upon the convex surface of another circle, which latter circle in this case is the pitch circle 16 of the inner gear. The 5 dedendum sections 18, or portions inside of the pitch circle 16 of the teeth, of the inner gear, are formed on hypocycloidal curves, that is, curves traced by a point on the circumference of a circle 17 which rolls upon 10 the inside surface of the pitch circle 16.

The addendum sections 19 of the teeth of the outer gear are formed on hypocycloidal curves, that is, curves traced by a point on the circumference of the circle 20 which rolls 15 upon the inside surface of the pitch circle 21 of the outer gear, while the dedendum sections 22 of the teeth of the outer gear are formed on epicycloidal curves, that is, curves traced by a point on the circumference of the circle 20 which rolls on the 20 convex surface of the pitch circle 21 of the outer gear. The circles 17 indicated as rolling on the outside and the inside of the pitch circle of the inner gear, and the circles 20, indicated as rolling on the outside and inside of the pitch circle of the outer gear, for illustrating the generation of the 25 epicycloidal and hypocycloidal curves of the gear teeth, are the same in diameter, and the diameter of these circles is the correct amount of eccentricity of the inner gear to the outer gear.

With this construction the gear teeth contact in various relations as the internally 30 toothed gear is rotated and drives the externally toothed gear, and this contact of the teeth is rolling, or in the nature of the contact of two cylinders. As the gears rotate the spaces between the teeth from the 35 point 23, where the teeth bottom, and the pitch circles 16 and 21 of the two gears are tangent, to the point 24 where the crests of the teeth engage, increase, while the spaces between the teeth, from the point of crest 40 engagement to the bottoming point, decrease, and a close seal is made between the gear teeth on the compression side.

In order to attain this required result in 45 pumps having the particular form of teeth described, and also teeth of other forms, which are commonly used, or may be used, it is necessary that the pitch circles of the two gears, which are eccentrically related, should be exactly tangent at one point. In 50 Figs. 2 and 3 this point is at 25. In the ordinary manufacture, and particularly in quantity production, it is difficult to obtain the exact eccentric relation of the gears, and it is the special object of this invention to 55 be able to, in a very simple and easy manner, obtain the correct eccentricity between the centers of the gears which will result in the pitch circles being tangent so that the 60 teeth will properly engage with a rolling 65 and sealing contact. Therefore, as above

stated, the arbor which is eccentric with the driving shaft is provided with an adjustable journal that is eccentric with relation to the arbor and to the driving shaft.

The preferred manner of accomplishing this adjustment is diagrammatically illustrated in Fig. 3, which shows the pitch circle 16 of the externally toothed gear represented in dotted lines as having an improper eccentricity with relation to the pitch 75 circle 21 of the internally toothed gear, and in full lines as in correct position to insure the necessary tangency of the pitch circles of the two gears to produce the desired 80 results. In the diagrammatic view the point 26 is the axis of the internally toothed gear, and the point 27 is the axis of the externally toothed gear. The point 28 represents the axis of the eccentric journal of the arbor which supports the externally toothed gear. 85 The radius 29 of the circle 30 indicates the correct amount of eccentricity of the gears. Therefore the point 27, which is the center of the arbor and the externally toothed gear, must when in correct position be somewhere 90 on the circle 30. With the construction illustrated and the axis 28 of the journal, which supports the arbor, in any accidental position, by rotating the journal, the axis 27 of the arbor of the externally toothed gear 95 may be swung around as from the dotted line position to the full line position so as to bring it into the circle 30, or at such a distance from the point 26, the axis of the internally toothed gear, that the gears will 100 have the correct eccentricity.

The journal may be provided with any convenient means for turning it, as a slot 31 for a screw driver or other tool, and after the proper adjustment is made the parts 105 may be secured by any suitable means as by driving a locking pin 32 between them.

This principle of construction allows any slight error in the eccentricity of the gears, such as is liable to occur during manufacture, to be quickly corrected, and this also permits any future adjustment of the gears to be made, if such should become necessary.

The invention claimed is:

1. A rotary pump comprising a casing, 115 a shaft journalled in the casing, an internally toothed gear mounted centrally on the shaft, an externally toothed gear eccentric within and co-acting with the internally toothed gear, and arbor for, and central 120 with, the externally toothed gear, and a rotatable journal for the arbor, the axes of the arbor and journal being eccentric to each other and each of said axes being eccentric to the axis of the shaft whereby by the rotation of said journal the eccentric adjustment of the externally toothed gear relatively to the internally toothed gear may be effected.

2. A rotary pump comprising a cas- 130

- ing, a shaft journalled in the casing, an internally toothed gear mounted centrally on the shaft, an externally toothed gear eccentric within and co-acting with the internally toothed gear, a support for, and central with, the externally toothed gear, and a rotatable journal for said support, the axes of the support and journal being eccentric to each other and each of said axes 5 being eccentric to the axis of the shaft whereby by the rotation of said journal the eccentric adjustment of the externally toothed gear relatively to the internally toothed gear may be effected, and means for 10 locking said support and journal against movement when the gears are in proper adjustment.
3. A rotary pump having a casing containing an internally toothed gear, an externally toothed gear surrounded by the internally toothed gear and eccentric thereto, and a normally stationary support for the externally toothed gear, said support being rotatably mounted in the casing eccentric to the axes of both gears, whereby the eccentricity of the axis of the externally toothed gear may be adjusted relatively to the axis of the internally toothed gear to ensure the tangency of the pitch circles 25 of the gears.
4. A rotary pump having a casing containing an internally toothed gear, an externally toothed gear surrounded by the internally toothed gear and eccentric thereto, a normally stationary support for the externally toothed gear, said support being rotatably mounted in the casing eccentric to the axes of both gears, whereby the eccentricity of the axis of the externally toothed gear may be adjusted relatively to the axis of the externally toothed gear to ensure the tangency of the pitch circles 30 of the gears, and means for locking said adjustable support against movement after it has been set in the desired adjustment.
5. A rotary pump having a casing enclosing an internally toothed gear, an externally toothed gear surrounded by the internally toothed gear, a normally stationary arbor supporting said externally toothed gear with its axis eccentric with relation to the axis of said internally toothed gear, and means extending to the exterior of the casing for adjusting the axis of the arbor with 35 relation to the axis of the internally toothed gear.
6. A rotary pump comprising a casing containing an internally toothed gear, an externally toothed gear surrounded by the internally toothed gear and eccentric thereto, an arbor supporting the externally toothed gear, and a rotatably adjustable journal for the arbor mounted in the casing, the axis of the journal being off-set from 40 the axis of the arbor and both axes being eccentric to the axis of the internally toothed gear, whereby the axis of the externally toothed gear relative to the axis of the internally toothed gear may be determined by rotatably adjusting said journal.
7. A rotary pump comprising a casing containing an internally toothed gear, a shaft extending into the casing for rotating the internally toothed gear, an externally toothed gear surrounded and engaged by the internally toothed gear, an arbor rotatably supporting the internally toothed gear, the axis of said arbor being eccentric to the axis of said shaft, and a journal supporting the arbor, said journal being rotatably mounted in the casing with its axis eccentric to the axis of the arbor and also eccentric to the axis of the shaft, whereby by rotating said journal the tangency of the pitch circle of the externally toothed gear and the pitch circle of the internally toothed gear may be obtained after the gears have 45 been enclosed in the casing.
8. A rotary pump comprising a casing containing an internally toothed gear, a shaft extending into the casing for rotating the internally toothed gear, an externally toothed gear surrounded and engaged by the internally toothed gear, an arbor rotatably supporting the externally toothed gear, the axis of said arbor being eccentric with relation to the axis of said shaft, a journal supporting the arbor, said journal being rotatably mounted in the casing with its axis eccentric to the axis of the arbor and also eccentric to the axis of the shaft, whereby by the rotation of said journal the tangency of the pitch circle of the externally toothed gear and the pitch circle of the internally toothed gear may be obtained after the gears have 50 been enclosed in the casing, and means for locking the journal against rotation after the required adjustment has been obtained.
9. A rotary pump having a casing containing an internally toothed gear, a shaft supported by the casing for rotating the internally toothed gear, an externally toothed gear surrounded and engaged by the internally toothed gear, an arbor rotatably supporting the externally toothed gear, the axis of said arbor being eccentric to the axis of said shaft and in a diametrical line extending from the locality of engagement of the crest points of the teeth of the gears through the axis of the shaft to the locality 55 of the bottoming of the teeth of the gears, and a rotatable journal for said arbor, the axis of said journal being eccentric to the axis of the shaft and arbor and out of said diametrical line, whereby by rotating said journal the axis of the externally toothed gear may be located in said diametrical line.
10. A rotary pump having a casing containing an internally toothed gear, a shaft supported by the casing for rotating the inter-

nally toothed gear, an externally toothed gear surrounded and engaged by the internally toothed gear, normally stationary means rotatably supporting the externally toothed gear, said supporting means being mounted in the casing with its axis eccentric with relation to the axis of the internally toothed gear and eccentric to the axis of the ex-

ternally toothed gear and rotatably adjustable to permit the relations of the axes of the gears to be changed and the tangency of the pitch circles of the gears to be ensured with the gears enclosed in the casing. ¹⁰
